CLAIM

We claim the ornamental design for a food slicer, as shown and described.

DESCRIPTION

FIG. 1 is a perspective view of a food slicer embodying the invention.

FIG. 2 is a front view of the food slicer shown in FIG. 1, the rear view being substantially identical thereto.

FIG. 3 is a side view of the food slicer shown in FIG. 1, the opposite side being substantially identical thereto.

FIG. 4 is top view of the food slicer shown in FIG. 1; and,

FIG. 5 is a bottom view of the food slicer shown in FIG. 1. The broken lines showing the environment of the claimed design form no part thereof.

1 Claim, 3 Drawing Sheets**FIG. 1**

FIG. 2***FIG. 3***

FIG. 4**FIG. 5**
